UNITED STATES PATENT OFFICE.

JOHN J. DAVIS, OF TIOGA, PENNSYLVANIA.

COKE-OVEN DOOR.

SPECIFICATION forming part of Letters Patent No. 374,942, dated December 20, 1887.

Application filed June 18, 1887. Serial No. 241,708. (No model.)

To all whom it may concern:

Be it known that I, JOHN J. DAVIS, of Tioga, in the county of Tioga, in the State of Pennsylvania, have invented new and useful Improvements in Coke-Oven Doors, of which the following, taken in connection with the accompanying drawings, is a full, clear, and exact description.

It is the general custom to close the doors of coke-ovens by means of a fire-brick wall built removably across the door and against the jambs thereof, and in some instances an iron door is hinged to an iron frame secured to the jambs of the opening of the oven, and a fire-brick lining is built up at the inside of the iron door to protect the same from the heat of the coal in process of being converted into coke.

Such methods and means for closing the doors of coke-ovens have several defects, of which may be mentioned the following: In bricking up the opening of the oven and plastering the said brick-work requires considerable time and labor, and in tearing down the brick-work and drawing the coke out of the oven more or less of the plaster becomes mixed with the coke, and thus impairs the commercial value of the same. When it is required to admit air over the coal in process of coking, perforations have to be made in the wall laid up as aforesaid by removing one or more of the bricks or pieces of brick from the upper portion of said wall, and subsequently to be replaced and made tight by plastering. All this occupies considerable time. Metallic doors, which are designed to obviate this latter defect, have their upper parts provided with ports and removable gates or stoppers over the ports; but said parts of the door are exposed to the heat from the interior of the oven, and are thus liable to become warped and burned.

Furthermore, the brick lining of the metallic door, as well as the brick wall aforesaid, allow the coal in the oven to come too near to the door at the base thereof, so that more or less of the coal at that locality is imperfectly coked. Aside from this, the construction of the hinged door with its ports and dampers or gates and the attachment of said door to the coke-oven are very expensive.

My invention is designed to obviate all of the aforesaid defects and objections; and to that end it consists in the improved means for

closing the discharge-openings of coke ovens, as hereinafter fully described, and specifically set forth in the claims.

In the annexed drawings, Figure 1 is a front elevation of a coke-oven door embodying my improvements. Fig. 2 is a vertical transverse section of the same. Fig. 3 is a horizontal transverse section on line *x*-*x*, Fig. 1; and Fig. 4 is a detached perspective view of the plate which closes the main portion of the door of the coke-oven.

Similar letters of reference indicate corresponding parts.

O denotes the coke oven, and D the opening through which to remove the coke. This opening I close during the coking process by the following improved devices: Upon the bottom of said opening I mount a metallic plate, A, which is separate and detached from the oven, and is formed with a horizontal outwardly-projecting base, *a*, by which it is supported in an upright position. Said plate extends completely across the opening, so as to abut against the jambs thereof, and extends from the bottom of the opening partway the height thereof, or nearly to the chord or spring line of the arch over the opening D. The top of the plate A is formed with an outwardly-projecting ledge, *b*, and in order to strengthen the plate I provide it with vertical ribs *c*.

C represents a metal shelf which projects outward from the top of the plate A, and, if desired, may be cast in one piece therewith; but for convenience of manipulating the said parts I prefer to form the shelf of a separate plate, which rests with its inner edge on top of the ledge *b*, and is supported at its outer edge adjustably in its elevation by a suitable prop, P, as best seen in Fig. 2 of the drawings.

The opening D is to be closed before the oven is charged with coal, and in closing said opening I first place the plate A in its hereinbefore-described position and deposit against the inner side thereof a bank of ashes or other analogous loose refractory material, as represented at I in Fig. 2 of the drawings, and close the opening over the top of the plate A by piling ashes or other suitable analogous material onto the shelf C, to reach to the crown of the arch over the opening D. Whenever it becomes necessary to admit air into the oven, the ashes on the shelf can be depressed or suf-

ficiently removed at the top to produce the requisite opening thereat, and this opening can be readily closed by replacing the removed ashes. The bank of ashes against the inner 5 side of the plate A serves to protect said plate from the heat of the coal in the process of coking, and at the same time keeps the coal a sufficient distance from the door to allow the air, which is admitted through the opening above 10 the shelf C, as aforesaid, to circulate across the top of the coal nearest the door, thus insuring perfect coking of all the coal in the oven.

It will be observed that by means of the 15 plate A and shelf C, with the banks of ashes deposited on said parts, as herein described, I obtain a coke-oven door which is very simple in its construction, and also simple, convenient, durable, and effective in its operation.

Having described my invention, what I claim 20 as new, and desire to secure by Letters Patent, is—

1. The combination, with a coke-oven, of the door-plate A, seated removably on the bottom of the discharge-opening of the oven

and reaching part way the height of said opening, and provided with the top ledge, b, and a shelf, C, supported with its inner edge removable on said ledge, substantially as and for the purpose specified. 25

2. The combination, with a coke-oven, of the plate A, seated removably on the bottom 30 of the discharge-opening of the oven and formed with the base a, top ledge, b, and ribs c c, the shelf C, supported with its inner edge removable on the ledge b, and the prop P, supporting the shelf at its outer edge adjustably 35 in its angle of inclination, substantially as described and shown.

In testimony whereof I have hereunto signed my name and affixed my seal, in the presence 40 of two attesting witnesses, at Tioga, in the county of Tioga, in the State of Pennsylvania, this 13th day of June, 1887.

JOHN J. DAVIS. [L. S.]
